(57) **CLAIM**

The ornamental design for an electric hot pot, as shown and described.

DESCRIPTION

FIG. 1 is a top perspective view of an electric hot pot showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a right side view thereof, shown in environmental use.

The broken lines depicting the extra pot insert in FIG. 8 illustrates environmental structure and forms no part of the claimed design. The dot-dash lines of FIG. 7 immediately adjacent to the claimed areas represent the boundaries of the design and form no part thereof. None of the broken lines form any part of the claimed design.
